UNITED STATES PATENT OFFICE.

WILLIAM S. HAMM, OF HUBBARD WOODS, ILLINOIS, ASSIGNOR TO THE ADAMS & WESTLAKE COMPANY, OF CHICAGO, ILLINOIS, A CORPORATION OF ILLINOIS.

DESIGN FOR A PENDENT LAMP.

43,193.

Specification for Design.

Patented Oct. 29, 1912.

Application filed August 23, 1912. Serial No. 716,751. Term of patent 14 years.

To all whom it may concern:

Be it known that I, WILLIAM S. HAMM, a citizen of the United States, residing at Hubbard Woods, county of Cook, and State of Illinois, have invented a new, original, and ornamental Design for Pendent Lamps, of which the following is a specification, reference being had to the accompanying drawing, forming a part thereof, and showing a side elevation of the lamp.

The lamp comprises a supporting member of the contour shown, being horizontal across its upper end and tapering downwardly through a portion of its length, and at its lower end flaring outwardly and terminating in a plurality of downwardly and

outwardly inclined arms; an annular member joined to the outer ends of the arms; a cylindrical member inclosed within the arms; an upwardly tapering member rising from the annular member and joining the cylindrical member; and a bulb shaped member below and of less diameter than the annular member.

I claim—

The ornamental design for a pendent lamp, as shown and described.

WILLIAM S. HAMM.
